CLAIM

The ornamental design for a position sensor, as shown and described.

DESCRIPTION

FIG. 1 is a perspective view of a position sensor;

FIG. 2 is a front view of a position sensor;

FIG. 3 is a right side view of a position sensor;

FIG. 4 is a rear view of a position sensor;

FIG. 5 is a left side view of a position sensor;

FIG. 6 is a top view of a position sensor; and,

FIG. 7 is a bottom view of a position sensor.
